CLAIM

The ornamental design for an ultrasonic probe, as shown and described.

DESCRIPTION

FIG. 1 is a perspective view of an ultrasonic probe showing our new design;

FIG. 2 is a front view thereof, the rear view being a mirror image of FIG. 2;

FIG. 3 is a left side view thereof;

FIG. 4 is a right side view thereof;

FIG. 5 is a top view thereof;

FIG. 6 is a bottom view thereof;

FIG. 7 is an enlarged end view of the cross-section thereof with the internal parts omitted, taken along the line 7-7 of FIG. 2;

FIG. 8 is a cross-section view thereof with the internal parts omitted, taken along the line 8-8 of FIG. 4; and,

FIG. 9 is a perspective view thereof showing the ultrasonic probe of FIG. 1 in a position of use.

The evenly dashed lines in FIGS. 1-9 depict portions of the ultrasonic probe that form no part of the claimed design. The
